MARTIN HEMLEB, OF ELIZABETH, NEW JERSEY, ASSIGNOR TO THE SINGER MANUFACTURING COMPANY, A CORPORATION OF NEW JERSEY.

SEWING-MACHINE.

1,005,831.

Specification of Letters Patent. Patented Oct. 17, 1911.

Application filed August 14, 1908. Serial No. 448,493.

To all whom it may concern:

Be it known that I, MARTIN HEMLEB, a citizen of the United States, residing at Elizabeth, in the county of Union and State 5 of New Jersey, have invented certain new and useful Improvements in Sewing-Machines, of which the following is a specification, reference being had therein to the accompanying drawings.

10 This invention has for its object to provide a machine for applying loops of thread or cord to the edges of fabrics, and more particularly to the overseamed scalloped edges of lace curtains, for ornamental purposes.

In its preferred form the improvement is embodied in a straight-away stitching machine, and comprises a thread-guide or carrier adapted to oscillate upon an axis sub- 20 stantially parallel with the needle-path across the line of feed and in advance of the needle, a thread-detainer or finger movable to and from the work-plate across the path of movement of said thread-guide and sub- 25 stantially parallel with the needle-path, and means for actuating said thread-guide and thread-detainer once only in the production of a succession or series of stitches, whereby each ornamental thread-loop is attached to 30 the work only at intervals of several stitches.

In the accompanying drawings, Figure 1 is a front side elevation of a Singer chain-stitch machine embodying the present improvement, Fig. 2 a plan thereof with the 35 overhanging portion of the bracket-arm removed to expose the parts beneath, Fig. 3 an end view of the machine with the casing for the parts beneath the work-plate removed, and Fig. 4 a detail front elevational view of 40 the edging thread handling members in different positions from those represented in Fig. 1.

The machine is constructed with the usual base 1 and bracket-arm 2, in which latter is 45 journaled the needle-actuating rock-shaft 3 having at its forward end a crank-arm 4 connected by means of a pitman 5 with a fixed collar 6 upon the needle-bar 7 carrying the needle 8. The rock-shaft 3 derives its 50 oscillatory movements through a lateral crank-arm 9 thereon connected by means of a pitman 10 with a crank-pin 11 upon the

balance-wheel 12, which, with the belt-wheel 13, is fixed to the rearward end of the main-shaft 14 which carries at its forward end 55 the single-chain-stitch rotary hook 15 co-operating with the needle 8 in the production of the chain-stitch seam.

The machine is provided with the usual feed-rocker mounted upon a supporting stud 60 16 and provided with an upright arm 17 to the upper end of which is pivotally secured by means of a pin 18 the feed-bar 19 formed at its outer end with a yoke 20 embracing the lifting cam 21 upon the main-shaft and 65 carrying the feed-dog 22. Operative movements are imparted to the feed-rocker by means of a bar 23 pivotally connected to the arm 17 by a pin 24 and provided with a yoke 25 embracing a cam or eccentric 26 70 upon the main-shaft adjacent the lifting cam 21. The bar 23 is provided with a forwardly extending member 27 connected by means of a stud-screw 28 with one end of a link 29 whose opposite end is connected by a 75 stud-screw 30 with the stitch-regulating lever 31 fulcrumed at 32 upon the machine frame. As will be observed, the position of the fulcrum-pin 30 determines the direction of movement of the actuating bar 23 under 80 the action of its cam 26 and hence the degree of movement of the rocker-arm 17 and operative throw of the feed-dog.

The machine is provided with the flat work-plate 33 in which is set the throat-plate 85 34 provided with a suitable feed-aperture 35, adjacent needle-slot 36 and a detainer receiving slot 37 to be later referred to.

The presser-foot 38 is attached to the lower end of a presser-bar 39 maintained 90 normally pressed downward by means of a spring 40 interposed between a fixed collar 41 thereon and the bottom of the upper bearing lug in the forward portion of the bracket-arm.

The presser-bar is provided adjacent its lower end with spaced collars 42 intermediate which is mounted the loose rocking sleeve 43 provided with a bowed lateral arm 44 having at its outer end a socket 45 in which 100 is secured by means of the set-screw 46 the upper end of the shank 47 of the edging-thread guide or carrier having a laterally and radially offset and contracted lower end

portion 48 provided with a thread-eye 49 to which the edging thread is led from a guide-eye 50 in the lower shank portion. As will be observed, the thread-carrier 48, 5 with its vertical axis of movement parallel with the needle-bar is adapted to oscillate across the feed line and in advance of the needle; and this movement is communicated through a second lateral arm 51 upon the 10 rocking sleeve 43 pivotally connected to one end of an adjustable pitman-rod 52 whose opposite end is similarly connected with the free end of a vibrating lever 53 having a boss 54 journaled upon the fixed fulcrum 15 stud-screw 55 and carrying intermediate its ends the roller-stud 56 entering a cam-groove 57 in the cam-wheel 58 which is mounted upon a fixed fulcrum stud 59 and provided with a bevel gear-wheel 60 meshing 20 with a bevel pinion 61 fixed upon the main-shaft 14. The gears 60 and 61 are proportioned to effect the rotation of the cam-wheel 58 at one-third the speed of the main-shaft 14. 25 Fixed upon the rearward portion of the work-plate 33 is a bracket 62 provided with spaced bearing lugs 63 in which is journaled the horizontal rock-shaft 64 provided at its rearward end with a fixed crank-arm 65 30 carrying a roller-stud 66 entering the lateral cam-groove 67 of the cam-wheel 58. Upon the opposite end of the rock-shaft 64 is fixed by means of the set-screw 68 the lateral crank-arm 69 provided at its outer end with 35 a radial socket in which is secured by means of the set-screw 70 the shank of the thread-detaining finger 71 offset laterally toward the needle-path and having a downwardly extending operative portion 72 parallel with 40 the needle and registering with the slot or aperture 37 in the throat-plate 34.

The rock-shaft 64 affords a fixed fulcrum upon which the finger 72 has a substantially rectilinear movement in a plane transverse 45 to the direction of operative movement of the edging-thread guide 48 and to the work-plate 33.

As indicated in the drawings, one side of the presser-foot is recessed in its forward 50 portion to embrace the path of movement of the needle 8 and thread-detaining finger 71, and slightly in advance of these members is disposed an edge-guide 73 mounted upon the work-plate adjustably by means of the screw 55 74 entering a slot 75 therein and provided with a guiding edge 76 and overhanging lip 77 to properly guide and confine the edge of the work in the stitching operation.

As the stitch-forming and feeding mechanisms are both actuated directly by connections with the main-shaft 14, it is evident that a feeding movement is imparted to the work for each reciprocation of the needle and

that stitches of uniform length are produced throughout the operation of the machine; 65 while the rotation of the cam-wheel 38 at one-third the speed of the main-shaft 14 causes the edging thread handling implements to perform their cycles of operation once only for each three stitches produced 70 by the machine.

In threading the machine, the needle thread is led from the thread supply over the guide-hook 78, thence downwardly through the tension 79 around the pin 80 75 and upward again through the tension over the thread-hook 81 and guide-hook 82 through the take-up tube 83 carried by the needle-bar, and thence downwardly through the tension 84 to the eye of the needle. The 80 edging thread is led from the source of supply through an eye in the rigid arm 85 fixed upon the rear side of the bracket-arm, thence through an eye in the pull-off arm 86, projecting rearwardly from the needle-actuating rock-shaft 3 in advance of said stationary arm, through an eye in the rearwardly extending and upturned projection 87 of the disk 88 between the tension-disks 89 and thence through the wire thread-guide 90 into 90 the guide-aperture 50 of the thread-carrier whence it is led through the delivery eye 49 to the work.

In the operation of the machine, the presser-foot is raised for the introduction 95 of the work, and subsequently lowered upon the latter, and the thread-carrier, mounted upon the presser-bar, follows such movements and thus remains clear of the work. In the position of the parts represented in 100 Figs. 1, 2 and 3, the thread-guide or carrier is in its extreme left-hand position, and the feed having taken place, its thread leads from its delivery eye rearward of the needle, which is raised for the initial stitch of the 105 series or succession. As soon as the needle has entered the goods in its initial descent, the thread-carrier moves across the line of feed and reaches its extreme right-hand position as the needle and detaining finger 71 110 are simultaneously raised. While the needle makes a complete reciprocation for the second stitch, the parts 48 and 71 remain in the same positions. As the needle descends for the third stitch, the detaining finger 71 also 115 descends in advance of the edging-thread which now leads from the second puncture rearward of the needle to the eye 49 of the thread-carrier, and after the points of the needle and detaining finger are well below the face of the work, the thread-carrier again 120 moves across the line of feed in front of the needle to its extreme position and the needle rises to initial position in readiness for the first descent of a succeeding cycle of operation to cross its thread upon the edging-

thread leading from the forward side of the detaining finger to the eye 49 of the thread-carrier for stitching the same upon the face of the work.

5 As will be observed the office of the detaining finger is to afford a turning point for the edging-thread off the goods such as is provided by the fastening stitches at intervals upon the face of the goods, the detaining finger thus providing slack edging-thread so as to form loose loops extending slightly beyond the edge of the work.

It is evident that, in case the loops of auxiliary thread should be desired upon the face of the fabric, the aperture for the thread-detaining finger may be omitted and the carrying arm 69 adjusted upon its rock-shaft to space the point of the finger slightly above the work-plate in its lower position, or the finger might readily be made elastic so as to yield when thrown into contact with the face of the fabric.

Having thus set forth the nature of the invention, what I claim herein is:—

25 1. In a sewing machine, the combination with the main-shaft, stitch-forming mechanism including a rectilinearly reciprocating needle operatively connected with and deriving one reciprocation for each revolution 30 of the main-shaft, and feeding mechanism, of a thread-guide movable crosswise of the direction of feed in advance of the needle-path, a thread-detainer with means for confining it to movement in a plane substantially parallel with the needle-path and the direction of feed and transverse to the path of movement of the thread-guide and adapted 35 for engaging and holding thread-loops carried by the thread-guide, a cam member, an operative connection including speed-reducing gearing between the same and said shaft, and independent connections intermediate said cam member and the thread-guide and the thread-detainer respectively, whereby they are adapted to 40 cooperate with each other once for each alternate stitch produced by the stitch-forming mechanism.

2. In a sewing machine, the combination 50 with stitch-forming mechanism including a reciprocating needle and feeding mechanism, of a thread-guide adapted to oscillate across the line of feed in advance of the stitch-forming mechanism upon and concentrically with a fulcrum disposed substantially parallel with the needle-path, the delivery orifice of said thread-guide being directed toward its axis of oscillation, means 55 for actuating the same, and a thread-detainer co-operating with said thread-guide and movable at one side of and substantially parallel with said needle-path, and means 60 for actuating the same.

3. In a sewing machine, the combination with stitch-forming and feeding mechanisms, of a thread-guide movable across the line of feed in advance of the stitch-forming mechanism, and a thread-detainer co-operating therewith and provided with means whereby it is confined to a substantially rectilinear path of movement in a plane transverse to that of the thread-guide, and mechanism acting independently of the stitch-forming mechanism and including an actuating member having a cycle of movement embracing that of a succession of stitch formations and independent connections between the same and said thread-guide and thread-detainer respectively.

4. In a sewing machine, the combination 80 with a rotary shaft and stitch-forming and feeding mechanisms operatively connected therewith, of a thread-guide movable across the line of feed in advance of the stitch-forming mechanism and a thread-detainer 85 co-operating therewith, a cam-wheel provided with cam grooves, an operative connection including speed-reducing gearing between the same and said shaft, two vibrating levers each carrying a stud entering one 90 of said cam grooves, and operative connections intermediate said levers and the thread-guide and the thread-detainer, respectively.

5. In a sewing machine, the combination 95 with stitch-forming mechanism including a reciprocating needle, feeding mechanism, and a presser-bar carrying a presser-foot, of a rocking sleeve upon said presser-bar provided with a lateral arm, a depending 100 thread-guide mounted upon said lateral arm of the rocking sleeve and formed with laterally and radially offset operative end portion containing a thread delivery eye, a thread-detainer for engaging and holding 105 loops of thread carried by the thread-guide, and means for oscillating said sleeve to move the thread-guide to and fro in advance of the needle-path.

6. In a sewing machine, the combination 110 with stitch-forming mechanism including a reciprocating needle, feeding mechanism, and a throat-plate provided with a feed opening and needle-hole and an adjacent aperture, of a thread-guide movable across 115 the line of feed in advance of said needle, a thread-detaining finger having an operative portion substantially parallel with said needle and adapted to enter and emerge from the aperture adjacent the needle-hole, 120 and actuating means for said thread-guide and thread-detaining finger.

7. In a sewing machine, the combination 125 with stitch-forming mechanism including a reciprocating needle, feeding mechanism, and a throat-plate provided with a feed

opening and needle-hole and an adjacent aperture, of a thread-guide movable across the line of feed in advance of said needle, a thread-detaining finger adapted to enter 5 and emerge from the aperture adjacent the needle-hole, and actuating means for said thread-guide and thread-detaining finger.

In testimony whereof, I have signed my name to this specification, in the presence of two subscribing witnesses.

MARTIN HEMLER.
